ELEVATOR SIGNALING SYSTEM

William F. Eames, Pittsburgh, Pa., assignor to
Westinghouse Electric Elevator Company, Chi-
cago, Ill., a corporation of Illinois

Application July 26, 1935, Serial No. 33,328

10 Claims. (Cl. 177—336)

My invention relates generally to electric signaling systems, and it has particular relation to such systems when employed in conjunction with elevator systems.

- 5 The object of my invention generally stated, is to provide an elevator signaling system which shall be simple, efficient and accurate in operation and which may be readily and economically manufactured and installed.
- 10 The principal object of my invention is to provide for immediately indicating to a person operating a call button at a floor, the elevator car which will stop at the floor in response to the operation of the call button.
- 15 An important object of my invention is to permit the operator of an elevator car to bypass a call assigned to his car in response to the operation of a call button at a floor and to indicate at the floor the next car that will stop at the floor.

Another object of my invention is to provide for lighting only one floor lantern at a floor in response to the operation of a call button to indicate the elevator car that will answer the call.

- 20 Still another object of my invention is to provide for overlapping the functioning of the successively energized zoning relays in an instant signal system for a bank of elevator cars.

A still further object of my invention is to provide a motor operated car selector for use in an instant signaling system for a bank of elevator cars.

Another object of my invention is to provide a notching car selector mechanism for use in an instant signaling system for a bank of elevator cars.

Other objects of my invention will in part be obvious and in part appear hereinafter.

My invention accordingly is disclosed in the embodiments hereof shown in the accompanying drawings and comprises the features of construction, combination of elements and arrangement of parts which will be exemplified in the constructions hereinafter set forth and the scope of the application of which will be indicated in the appended claims.

For a more complete understanding of the nature and scope of my invention, reference may be had to the following detailed description taken in connection with the accompanying drawings, in which

Figure 1 illustrates the arrangement of one car of a bank of elevator cars in a hatchway,

Fig. 2 illustrates the layout of a portion of the

floor selector individual to the elevator car shown in Fig. 1.

Fig. 3 illustrates diagrammatically a portion of the zoning network for a bank of three elevator cars.

Fig. 4 illustrates diagrammatically a motor driven car selector system for two floors organized in accordance with this invention.

Fig. 4—A illustrates the physical arrangement of the contact members and operating windings of the various relays and switches shown in Fig. 4.

Fig. 5 illustrates diagrammatically a system similar to that shown in Fig. 4, except that notching drive mechanisms are provided for operating the car selector switches, and

Fig. 5—A illustrates the physical arrangement of the contact members and operating windings of the relays and switches shown in Fig. 5.

According to my invention, I provide for indicating to a person operating a hall button of a bank of elevator cars the particular elevator car which will answer the call as soon as it has been selected. As soon as the indication of the car which will stop at the floor has been given, the person may immediately place himself in front of the doorway or hatchway entrance to the car and he will be ready to enter the selected car as soon as it arrives at the floor. It is then unnecessary for the person to await the arrival of the elevator car before he is informed as to the particular car which will answer his call. The car nearest the floor where a call button is operated is selected by means of a car selector switch for each floor. It is desirable that the car selector switches be operated at uniform speeds and for that purpose I have provided two different drives.

The car selector switch for each floor comprises several banks of contact members, each contact member being individual to an elevator car in the bank. One of these banks comprises a car selecting bank and a contact arm is provided for successively engaging the contact members thereof until the contact member, individual to the car nearest to the floor at which the car selector switch is located and where a call is registered, is engaged. At this time, the contact arm of a floor lantern bank of contact members engages a contact member individual to the floor lantern of the elevator car nearest the floor and it is lighted, thereby indicating the car which has been selected to answer the call. This operation may take place and the floor lantern may be lighted while the elevator car is still several

floors away from the floor where the call is registered.

In one modification of the invention, an electric motor is arranged to operate the car selector switch. The motor is initiated in operation as soon as the call button individual thereto at a floor is operated, and it continues in operation to move the contact arms of the selector switch past the various contact members of the contact banks at a uniform speed until the contact member of the car selecting bank individual to the nearest car is engaged.

In another modification of the invention, the car selector switch is arranged to be operated by means of a notching drive mechanism. That is, a pawl and ratchet mechanism is provided which is arranged to step the contact arms of the various banks from one contact member to another, until the desired selection has been made.

In order that consistent operation of the system will result and an accurate selection of the nearest car to the floor may be made, it is desirable that the contact arms be moved past the various contact members of the various banks at a uniform speed. It is then possible to stop the car selector switch as soon as the car nearest the floor has been selected and there is little likelihood that the car selector switch will overshoot or undershoot the desired selecting position as might be the case if the car selector switch were operated at variable speeds.

In order to select the elevator car nearest to the floor where a call is registered, a zoning system is provided which allocates certain of the floors to each car depending upon the positions of the cars in the hatchways. A floor selector individual to each car is provided which is arranged to operate in conjunction therewith to successively effect the energization of zoning relays. Thus, when a call is registered at a certain floor only the car nearest to that floor and moving in a direction of travel for which the call is registered will have the call assigned to it. Because of the functioning of the zoning system, no other car can receive the call. In order to prevent the zone from being transferred to another car as the elevator cars pass from one floor to another, the brush which is arranged to engage the zone segments of the floor selector may be made of sufficient length to bridge two of the segments. At no time, therefore, will the zoning relays of a particular car be completely deenergized while it is travelling in the hatchway. Stated differently, before the last zoning relays are deenergized, the next zoning relays are energized, thereby providing a certain degree of overlap which prevents the extension of the zone beyond a particular car.

Under certain conditions, it may be desirable to by-pass a call. Such, for example, may be the case when the car is fully loaded and can take on no more passengers. A by-passing switch is provided in each car for operation by the operator. As soon as the by-passing switch is operated, the zone of the next car is automatically extended to include the floors in the zone which are allocated to the car in which the by-passing switch is operated. Prior to the operation of the by-passing switch in a car certain of the floor lanterns individual to that car may have been lighted in response to calls at various floors in its zone. On operation of the by-passing switch these floor lanterns will be extinguished and the floor lanterns at the same floors individual to the next car which app-

riates the zone of the preceding car will be lighted. The by-passing circuits include a by-passing bank of contact members included on the car selector switch and operable therewith, as will be set forth in detail hereinafter.

5

Referring now particularly to Fig. 1 of the drawings, it will be observed that car B of a bank of cars comprising cars A, B and C is there illustrated. The elevator car may be supported in its hatchway by means of a cable 10 which is passed over a sheave 11 and counterweighted by suitable counterweights 12. A motor 13 is provided for operating the sheave 11 to move the car B in the hatchway. The motor 13 is provided with a shaft extension 14 which is arranged to operate the brush carriage 15 of a floor selector shown generally at 16 by rotating a lead screw 17.

10

15

It will be observed that only the fifth, sixth, seventh and eighth floors are illustrated in Fig. 20 1. It will be understood, however, that the remaining floors will be a duplicate of those illustrated and that as many floors may be provided as required. Each elevator car has individual thereto at each floor two hall lanterns, one for 25 each direction of travel. Thus, at the fifth floor the down hall lantern 5BDL is provided individual to car B at that floor and, when lighted, indicates that car B will stop at that floor in the down direction. Likewise, for the up direction 30 for car B hall lantern 5BUL is provided. Similarly, for the sixth and seventh floors, up and down floor lanterns are provided.

20

25

In order to stop the elevator at each floor call buttons are provided. At the fifth floor for stopping the elevator car in the down direction, the call button 5D is provided. Similarly, for the up direction a call button 5U is provided. Likewise, for the sixth and seventh floors call buttons are similarly provided.

30

The car B is provided with a signal light BS which is arranged to be lighted on the operation of a call button to indicate to the operator that he is to stop the car in response to a call. In the event that he does not wish to stop at the floor to answer the call, he may operate a by-pass button BPS in order to transfer the call to the next car nearest the floor. A master switch MS is also provided for operating the elevator car in either direction.

40

45

A portion of the floor selector for car B is illustrated in Fig. 2 of the drawings. When car B moves in the down direction, the rotation of the lead screw 17 is such as to cause contact brushes BDS, BDZ and BDX carried by the brush carriage 15 to engage corresponding rows of segments while contact brushes EUX and BUZ and EUS also carried by the brush carriage 15 are maintained out of engagement with their corresponding segments. As illustrated, the contact brush BDS is arranged to successively engage down car signal segments 4BDS through 8BDS. Contact brush BDZ is arranged to successively engage down zone feed segments 4BDZ through 8BDZ. It will be observed that the contact member BDZ is shown in elongated form to indicate that it bridges the successive down zone feed segments in order to prevent the zones from overlapping. It will be understood, of course, that other means may be employed for preventing the zones from overlapping. Contact brush BDX is arranged to successively engage down cancelling segments 4BDX through 8BDX for the purpose of cancelling the calls after they have been answered. When the elevator car B moves in the up direc- 50

50

55

60

65

70

75

75

tion, the contact brushes BUX, BUZ and BUS are arranged to successively engage corresponding up segments, as illustrated.

Referring now particularly to Fig. 4 of the drawings, it will be observed that the circuits associated with the down call buttons at the fifth and sixth floors only are illustrated. Since the circuits for the up call buttons for the fifth and sixth floors as well as for the remaining floors 10 are substantially a duplicate of the circuits illustrated in Fig. 4 of the drawings, it is unnecessary to illustrate them in detail.

Associated with each of the down call buttons 5D and 6D are call storing relays 5DR and 6DR, respectively. Each of the call storing relays is provided with a main operating winding bearing the same reference character as the relay. In addition, cancelling windings 5DRN and 6DRN are provided for releasing the call storing relay 20 to cancel the call after it has been answered by the elevator car arriving at the floor. The ampere turns of the neutralizing windings on energization are arranged to oppose the ampere turns of the main windings and, as a result, the latter are 25 neutralized to permit the call storing relays to be returned to the normal non-operated condition.

Individual to each floor is provided a car selector switch. At the fifth floor, car selector switch 5S is provided while at the sixth floor car selector switch 6S is provided. Each of the switches includes three banks of contact members, each contact member of which is individual to one of the three elevator cars comprising the bank. Thus, the car selector switch 5S is provided with a floor 35 lantern bank of contact members comprising contact members 5SAL, 5SBL and 5SCL, each individual to cars A, B and C respectively. A contact arm 5L is arranged to successively engage the contact members. A by-passing bank of contact members 5SAP, 5SBP and 5SCP is provided each individual to one of the cars A, B and C, respectively. A contact arm 5P is arranged to successively engage these contact members. In order to select the elevator car nearest the 40 floor where a call is registered, car selecting bank comprising contact members 5SAR, 5SBR and 5SCR is provided, each individual to the cars A, B and C, respectively. A contact arm 5R is provided for successively engaging the contact members of this bank. In like manner, the car selector 45 6S is provided with similar contact members and contact arms, the prefix 6 being provided to indicate that the various elements are individual to the car selector switch 6S at the sixth floor.

In order to operate the car selector switches 5S and 6S, direct-current motors 5M and 6M may be provided. Each of the motors comprises an armature 20 which is arranged to rotate a shaft 21 through a suitable gear reducing mechanism 22, as illustrated. A shunt field winding 23 is also provided for each of the motors. The contact arms 5L, 5P and 5R of the car selector switch 5S are mounted on the shaft 21 of the motor 5M. Similarly, the corresponding contact arms of the car selector switch 6S are mounted on the shaft 21 of the motor 6M. Since a motor is provided for driving the shaft 21 and further since it will operate at a constant speed, it is then possible to operate the various contact arms past their respective contact members at a uniform speed. Furthermore, the motors 5M and 6M are so constructed that they will reach operating speed substantially immediately after the contact arms leave any initial position. Therefore, the contact arms will always 50 engage the corresponding contact members of

their respective banks and pass them at the same speed. When the particular car nearest the floor where a call is registered has been selected, it will be possible to provide for stopping the drive motors within the necessary degrees of accuracy 5 to insure that the nearest car has been selected.

Since it is desirable to allocate the certain floors to a particular car, depending upon its location in the hatchway, auxiliary zoning relays 5ADY, 5BDY and 5CDY are provided individual to the fifth floor. These relays are arranged to be energized as the contact brush BDZ successively engages the various down zone feed segments. That is, the contact brush BDZ is arranged to successively energize the auxiliary zoning relays for car B while similar contact brushes of floor selectors for cars A and C are arranged to energize their corresponding auxiliary zoning relays, for example, 5ADY and 5CDY of cars A and C. 20

In response to the operation of the auxiliary zoning relays, for example 5BDY and 6BDY, zoning relays 5DZ and 6DZ are operated. The zoning relays 5DZ and 6DZ are arranged to open their contact members to maintain the floors 25 ahead of a particular car allocated to that car and not to another car.

As soon as the car selector switch individual to a floor where a call is registered has been operated to a position corresponding to the car 30 nearest to the floor, a holding relay is operated which prevents further functioning of the car selector switch. At floors five and six, holding relays 5H and 6H are provided, respectively. These relays not only stop further functioning 35 of the car selector switch but also complete circuits for energizing the floor lantern individual to the car which will answer the call at the floor where it is registered.

In the event that the operator does not wish 40 to answer the call, he may operate the by-pass switch BPS in car B, for example, to operate a by-passing relay BBP. Similarly, cars A and C are provided with by-passing switches APS and CPS, respectively, which are arranged to effect 45 the energization of by-passing relays ABP and CBP, respectively. The by-passing relays are arranged to cooperate with the by-passing bank of contact members of the car selector switches for releasing the car selector switch to select the 50 next nearest car to the floor and to light the hall lantern individual thereto at the floor where a call is registered.

In the diagram illustrated in Fig. 4 of the drawings, it will be observed that conductors or 5 main busses L1, L2 and L3 are provided. The conductors L1 and L3 may be connected to the same polarity of a direct current source while the conductor L2 is connected to the opposite polarity of the source. This circuit arrangement has been employed for the purpose of convenience in showing the auxiliary zoning relays, the zoning relays and the circuits associated therewith.

It will also be observed that in Fig. 4 of the 6 drawings, only the contact members surrounded by the dot and dash lines indicated in Fig. 3 of the drawings are illustrated. The remaining contact members of the zoning system shown in Fig. 3 are illustrated for the purpose of more 7 clearly setting forth the functioning of the zoning system. Appropriate reference characters similar to those employed for the fifth and sixth floors have been applied for the remaining floors. Since the circuit connections to the operating 7

windings of the various auxiliary and zoning relays for the remaining floors will be substantially a duplicate of those shown for the fifth and sixth floors, it is unnecessary to illustrate them in detail herein.

In considering the circuit connections for the zoning system illustrated in Fig. 3, it may be assumed that car A is at the third floor, car B is at the eighth floor and car C is at the twelfth floor and that they are all moving in the down direction. The auxiliary and zoning relays individual to these floors will be energized. As a result a call registered at the second floor for the down direction will be allocated to car A, a call registered at the fifth floor will be allocated to car B, while a call registered at the tenth floor will be allocated to car C. The principal circuits involved under the assumed conditions are shown in heavy lines while the remaining circuits which for the assumed conditions are not involved are shown by lighter lines. Thus, for example, as soon as a person operates the down button 5D at the fifth floor, the floor lantern 5BDL individual to car B at the fifth floor will substantially immediately be lighted to indicate that car B will answer the call despite the fact that car B is at the eighth floor at the time that the call is registered.

In the event that the operator of car B does not wish to answer the call at the fifth floor, he may operate the by-pass switch BPS. As a result, the fifth floor will be taken out of the zone allocated to car B and it will be allocated to car C. The particular circuit connections and relay operation involved will be set forth in detail hereinafter.

In describing the functioning of the signaling system illustrated in Fig. 4 of the drawings, it will be assumed that the conductors L₁, L₂ and L₃ are properly energized, that a call is registered at the fifth floor by the operation of the down call button 5D and that under the assumed conditions the fifth floor is allocated to car B, and that at the time the call is originated car B is at the eighth floor. In response to the operation of the down call button 5D, a circuit is completed for energizing the main operating winding of the call storing relay 5DR which may be traced as follows: L₁, 5D, 5DR, L₂. At contact members 5DR₁ a holding circuit is completed for maintaining the main operating winding 5DR energized, and, therefore, the down call button 5D may be released.

The motor 5M which is arranged to drive the car selector switch 5S, is then energized and the shaft 21 is rotated to cause the contact arms carried thereby to successively engage the various contact members of the various contact banks. It will be observed that the contact arms extend in both directions from the shaft 21, so that each end thereof is arranged to successively make contact engagement with the members of the contact banks. The circuit for energizing the motor 5M may be traced as follows: L₁, armature 20, 5H₁, 5DR₂, L₂. It will be observed that the shunt field winding 23 is energized in parallel circuit relation with the armature 20.

Since the car B is assumed to be at the eighth floor, the auxiliary zoning relay 8BDY and the zoning relay 8DZ will be energized to close and open the contact members 8BDY₂ and 8DZ₂, as illustrated in Fig. 3. The circuit connections for energizing the auxiliary zoning relay 8BDY and the zoning relay 8DZ are identical with those for energizing the auxiliary zoning relay 6BDY and

the zoning relay 6DZ at the sixth floor. Therefore, the circuits for energizing the sixth floor zoning relays will be traced and it will be understood that corresponding circuits may be provided for the eighth floor zoning relays. The circuit for energizing the operating winding of the auxiliary zoning relay 6BDY may be traced as follows: L₂, 6BDY, segment 6BDZ, brush BDZ, BDP₂, L₃. The sixth floor zoning relay 6DZ is energized over a circuit which may be traced as follows: L₂, 6DZ, 6BDY₁, L₃.

As the contact brush BDZ is transferred from down zone feed segment to down zone feed segments, the corresponding auxiliary zoning relays are successively energized and, due to the fact that the contact brush BDZ is sufficiently long to bridge two succeeding down zone feed segments, the next auxiliary zoning relay and consequently the next zoning relay are energized before the preceding auxiliary zoning relay and zoning relay are deenergized.

As soon as the contact arm 5R of the car selector switch 5S engages the contact member 5SBR individual to car B, a circuit is completed under the assumed condition for effecting the energization of the holding relay 5H. Assuming that the zoning relay 6DZ is energized, this energizing circuit may be traced as follows: L₁, 5H, 5R, 5SBR, 5DZ₂, 6BDY₂, L₂. The circuit for energizing the operating winding of the holding relay 5H when the elevator car B is at the eighth floor may be traced as follows, transferring the circuits to include those shown in Fig. 3: L₁, 5H, 5SBR, 5DZ₂, 6DZ₂, 7DZ₂, 8BDY₂, L₂.

As car B continues to move in the down direction, the contact brush BDZ engages the down zone feed segment 7BDZ, thereby effecting the energization of the auxiliary zoning relay and the zoning relay at the seventh floor, and transferring the energizing circuit for the operating winding of the holding relay 5H through contact member 7BDY₂ to the conductor L₂. It will, therefore, be understood that the contact arm 5R continues to rotate until the contact member of its car selecting bank is energized which corresponds to the elevator car that is nearest to the fifth floor. As soon as this contact segment is engaged, the holding relay 5H is energized and at contact members 5H₁, the previously traced energizing circuit for the motor 5M is opened insofar as the armature 20 is concerned and no further movement of the shaft 21 and the contact arms carried thereby takes place. Since the movement of the contact arms past their individual contact segments is at a uniform speed, it is possible to so arrange the opening of contact members 5H₁ that the contact arms will be always stopped in the proper positions.

At contact members 5H₃ a holding circuit is completed for the operating winding of the holding relay 5H which prevents the transfer of the call registered at the fifth floor to another car, car C for example, should it pass car B in its downward direction of travel. This holding circuit may be traced as follows: L₁, 5H, 5P, 5SBR, 5BP₃, 5H₃, 5DR₂, L₂.

Since the contact arm 5L is now in engagement with the contact member 5SBL of the floor lantern bank of contact members, a circuit is completed as soon as contact members 5H₂ are closed for lighting the hall lantern 5BDL individual to car B in the fifth floor. This circuit may be traced as follows: L₁, 5H₂, 5L, 5SBL, 5BDL, L₂. It will now be understood that the floor lantern individual to car B at the fifth floor is lighted.

as soon as the car selector switch 5S has effected the selection of the car nearest to the fifth floor, in this case car B, even though this car is several floors away and, for example, is at the eighth floor. Because of the holding circuit established through contact members 5H3, the selection will be maintained and the floor lantern 5BDL will remain lighted until the call is cancelled or bypassed. The person who operated the down call button 5D may then place himself in front of the doorway or hatchway entrance for car B at the fifth floor, and he will be ready to enter the car as soon as it arrives at the floor.

The operator is informed that he is to stop at the fifth floor by the lighting of the car signal lamp BS. This lamp is lighted as soon as contact brush BDS of the floor selector engages down car signal segment 5BDS. This circuit may be traced as follows: L1, 5H2, 5L, 5SBL, 5BDS, BDS, BS, L2. It will be observed that the contact brush BDS which is arranged to engage the down car signal segments is given a lead of one floor, so that when car B is at the sixth floor, the operator is informed that he is to stop at the next floor. It will be understood that the contact member BDS may be given a greater lead, for example, two or three floors in the event that it is desired to inform the operator sooner that he is to stop at a particular floor.

In the event that the operator does not wish to stop at the fifth floor, he may operate the bypass switch BPS. As a result of the operation of the by-pass switch BPS, a circuit is completed for energizing the operating winding of the bypass relays BBP individual to car B. This circuit may be traced as follows: L2, BPS, BBP, L3. It will be assumed that the car signal BS is lighted as the elevator car passes the sixth floor, and, therefore, that the auxiliary zoning relay 6BDY and the zoning relay 6DZ are energized. The energization of the by-pass relay BBP opens the contact members BBP2 in the previously traced energizing circuit for the operating winding of the auxiliary zoning relay 6BDY. As a result, it is deenergized and, in turn, the contact members 6BDY1 open the energizing circuit for the zoning relay 6DZ. At contact members BBP3 which are associated with contact member 5SBP of the by-passing bank of contact members, the previously traced holding circuit for the operating winding of the holding relay 5H is opened. This relay is deenergized and contact members 5H1 are reclosed to again start the motor 5M in operation to rotate the shaft 21. Since the auxiliary zoning relay and the zoning relay associated with the sixth floor are deenergized, the fifth floor is now transferred or allocated to the next car nearest the fifth floor which under the assumed conditions is car C. The call then is transferred to car C and the drive motor 5M is stopped as soon as the contact arm 5R engages the contact member 5SCR of the car selecting bank of contact members in a manner similar to that described for the stopping of the motor 5M and the selection of car B.

Assuming, however, that the operator does not depress the by-pass switch BPS but elects to stop at the fifth floor, he will operate the master switch MS to the off position and will stop at the fifth floor.

When the elevator car B is at the fifth floor, contact brush BDX is in engagement with down cancelling segment 5BDX. Connected in series circuit relation with contact member BDX are two contact members 30 and 31, contact members

30 being normally in the open condition and contact members 31 being normally in the closed condition, as indicated in Fig. 4 of the drawings. These contact members are arranged to complete a circuit to the contact brush BDX only when the elevator car is leaving a floor. These contact members are associated in the control system and may be arranged for operation as illustrated in the copending application of E. M. Bouton and W. F. Eames, Serial No. 736,672, filed July 24, 1934, and assigned to the assignee of this application. Assuming that the elevator car B is leaving the fifth floor, the circuit for energizing the cancelling winding 5DRN of the call storing relay 5R may be traced as follows: L1, 5DR1, 5DRN, 5BDX, BDX, 30, 31, L2. Since the call storing relay 5DR is deenergized, contact members 5DR2 are opened and the holding circuit for the operating winding of the holding relay 5H is opened. The contact members 5H2, in the previously traced energizing circuit for lighting the down floor lantern 5BDL, are opened and the floor lantern 5BDL is extinguished.

Referring now particularly to Fig. 5 of the drawings, it will be observed that the system there shown is substantially the same as that shown in Fig. 4 of the drawings with the exception of the mechanism which is employed to rotate the shaft 21 for moving the contact arms carried thereby past the various banks of contact members. As illustrated, a notching mechanism shown generally at 35 is provided having an operating winding or electromagnet 6N at the sixth floor which is arranged to attract an armature 36 against the force of a biasing spring 37. A pawl 38 is arranged to be operated by the armature 36 and it engages a ratchet wheel 39 mounted on the shaft 21. At each energization and deenergization of the operating winding 6N, the ratchet wheel 39 is advanced one notch which corresponds to a movement of the contact arms carried by the shaft 21 from engagement with one set of contact members to the next set of contact members of the various banks. An auxiliary notching relay 6AN is provided to cooperate with the operating winding 6N in its function. As shown, corresponding relays 5N and 5AN are provided for operating the ratchet wheel 39 of the car selector switch 5S at the fifth floor.

Since the functioning of the system shown in Fig. 5 is the same as that described hereinbefore in connection with the circuits shown in Fig. 4, except for the operation of the notching drive mechanism 35, the description of the circuits shown in Fig. 5 will be limited to that necessary to set forth the functioning of the notching drive mechanism. As soon as a call is registered, for example, at the fifth floor, the call storing relay 5DR is energized, as set forth hereinbefore, and at contact members 5DR2 a circuit is completed for energizing the operating winding 5N. This circuit may be traced as follows: L1, 5N, 5AN1, 5DR2, L2. The energization of the operating winding 5N causes the ratchet wheel 39 to be stepped one notch at the same time contact members 5N1 are closed to complete a circuit for energizing the operating winding of the auxiliary notching relay 5AN. This circuit may be traced as follows: L1, 5AN, 5N1, 5DR2, L2. At contact members 5AN1, the previously traced energizing circuit for the operating winding 5N is opened. It is deenergized and the armature 36 is returned by the spring 37 to the non-operated position. This sequence of operation continues and the ratchet wheel 39 is successively stepped to move

the contact arms carried by the shaft 21 from position to position until the contact arm 5R engages a contact member corresponding to the car nearest the fifth floor.

5 Under the assumed conditions, car B is the car nearest the fifth floor and, as a result, when the contact arm 5R engages the contact member 5SBR, a circuit is completed for energizing the operating winding of the holding relay 5H, as previously traced. At contact members 5H1, the contact members 5N1 are shunted, thereby maintaining the auxiliary notching relay 5AN energized and stopping further operation of the notching drive mechanism 35. At this time, the floor 10 lantern 5BDL corresponding to car B at the fifth floor will be lighted to indicate to the person at the fifth floor that car B will stop to answer the call.

In the event that the operator of car B wishes 20 to by-pass the fifth floor, he may operate the by-pass switch BPS in the manner set forth hereinbefore, to release the holding relay 5H and permit the notching drive mechanism to stop the car selector switch 5S until the contact arm 5R engages a contact member of its bank corresponding 25 to the next car nearest the fifth floor.

Since certain further changes may be made in the foregoing constructions and different embodiments of the invention may be made without departing from the scope thereof, it is intended that all matter shown in the accompanying drawings or set forth in the foregoing description shall be considered as illustrative and not in a limiting sense.

35 I claim as my invention:

1. A signaling system for a bank of elevator cars operable past a plurality of floors comprising a plurality of floor lanterns, one for each car at each floor, a call means at each floor common to 40 all the cars, a car selector mechanism including a rotatable motor for each floor, means responsive to the position of the cars and to operation of a call means at a floor for causing the selector mechanism for that floor to select the car nearest 45 said floor for the direction of the call to answer the call, means responsive to operation of said mechanism for lighting the floor lantern at said floor individual to the selected car, a by-pass device for each car, and means responsive to operation 50 of the by-pass means of said selected car for effecting operation of said selector mechanism to extinguish said floor lantern, select to answer the call the next car nearest said floor for the direction of said call and light the floor lantern 55 individual thereto.

2. A signaling system for a bank of elevator cars operable past a plurality of floors comprising a plurality of floor lanterns, one for each car at each floor, a call means at each floor common to 60 all the cars, a car selector mechanism including a uniform speed driving mechanism, means responsive to the position of the cars and to operation of a call means at a floor for causing the selector mechanism for that floor to select the car nearest said floor for the direction of the call to answer the call, means responsive to operation 65 of said mechanism for lighting the floor lantern at said floor individual to the selected car, a by-pass device for each car, and means responsive to operation 70 of the by-pass means of said selected car for effecting operation of said mechanism to extinguish said floor lantern, select the next car nearest said floor for the direction of said call and light the floor lantern individual thereto.

75 3. A signaling system for a bank of elevator cars

operable past a plurality of floors comprising, in combination, signaling means individual to each floor and to each car, call means individual to each floor, a car selecting mechanism individual to each floor and provided with a plurality of 5 contact members, each contact member being individual to a car, an arm normally movable in only one direction for successively engaging said members, a rotating electric motor having a substantially constant speed characteristic through a 10 variable range of loads for driving each selecting mechanism, means operable in response to the operation of the call means at a floor for causing the motor for the floor of the operated call means to move the arm of its associated floor 15 selector in its normally movable one direction to operate said selecting mechanism to select the car nearest said floor, and means responsive to operation of said selecting mechanism for operating the signaling means at said floor individual 20 to the selected car to indicate the selection.

4. A signaling system for a plurality of elevator cars operable past a plurality of floors comprising, in combination, a floor lantern individual to each floor and to each car, a call button individual to each floor; a car selector individual to each floor including a car selecting bank of contact members each individual to a car, a floor lantern bank of contact members each individual to a floor lantern at the floor, and a movable contact arm individual to each bank and disposed to successively engage the contact members thereof; a rotating motor having a substantially constant speed characteristic through a variable 30 range of loads individual to each selector, and 35 means responsive to operation of a call means at a floor for causing the motor corresponding thereto to move the contact arms of its selector past their respective contact members to select the car nearest said floor and to light the floor 40 lantern at said floor individual to the car selected.

5. A signaling system for a plurality of elevator cars operable past a plurality of floors comprising, in combination, a floor lantern individual to 45 each floor and to each car, a call button individual to each floor; a car selector individual to each floor including a car selecting bank of contact members each individual to a car, a floor lantern bank of contact members each individual 50 to a floor lantern at the floor, and a movable contact arm individual to each bank and disposed to successively engage the contact members thereof; a rotating motor having a substantially constant speed characteristic through a variable range of 55 loads individual to each selector, means responsive to operation of a call means at a floor for causing the motor corresponding thereto to move the contact arms of its selector over their respective contact members at substantially the same speed, and means responsive to said operation of said call means and to the contact arms engaging the contact members corresponding to the selector car for stopping said motor and for effecting the lighting of the floor lantern for said 65 selected car at said floor.

6. A signaling system for a plurality of elevator cars operable past a plurality of floors comprising, in combination, a floor lantern individual to each floor and to each car, a call button individual 70 to each floor; a car selector switch individual to each floor including a car selecting bank of stationary contact members each individual to a car, a floor lantern bank of stationary contact members each individual to a floor lantern at the 75

floor, and a movable contact arm individual to each bank and movable in a predetermined path to successively engage the contact members thereof; means for preventing movement of each of 5 said contact arms out of its said predetermined path, a notching mechanism having driving connection with said contact arms, and means operable in response to the operation of a call button at a floor for effecting the successive energization 10 and deenergization of said notching mechanism to step said contact arms from contact member to contact member until the contact members individual to the car nearest said floor for the direction of the operated button are engaged thereby, 15 and means responsive to engagement of said contact arms and the contact members individual to said nearest car for lighting the floor lantern of said nearest car at said floor.

7. A signaling system for a plurality of elevator 20 cars operable past a plurality of floors comprising, in combination, a floor lantern individual to each floor and to each car, a call button individual to each floor; a car selector switch individual to each floor including a car selecting bank of stationary contact members each individual to a car, a floor lantern bank of stationary contact members each individual to a floor lantern at the floor, and a movable contact arm individual to each bank and movable in a predetermined path 25 to successively engage the contact members thereof; means for preventing movement of each of said contact arms out of its said predetermined path, and motive means responsive to operation of a call button at a floor for operating the contact arms of the floor selector for that floor to successively engage its stationary contact members until the contact members individual to the car nearest said floor for the direction of the operated button are engaged thereby, 30 and means responsive to the engagement of said arms and said contact members individual to said car for stopping said motive means and for lighting the floor lantern at said floor for said car.

8. A signaling system for a plurality of elevator 45 cars operable past a plurality of floors comprising, in combination, a floor lantern individual to each floor and to each car, a call button individual to each floor; a car selector switch individual to each floor including a car selecting bank of stationary contact members each individual to a car, a floor lantern bank of stationary contact members each individual to a floor lantern at the floor, and a movable contact arm individual to each bank and movable in a predetermined path 50 to successively engage the contact members thereof; means for preventing movement of each of said contact arms out of its said predetermined path,

5 mined path, and motive means responsive to operation of a call button at a floor for operating the contact arms of the floor selector for that floor to successively engage its stationary contact members until the contact members individual to the car nearest said floor for the direction of the operated button are engaged thereby, and means responsive to the engagement of said arms and said contact members individual to said car for stopping said motive means and for lighting the 10 floor lantern at said floor for said car.

9. A signal system for a bank of elevator cars operable past a plurality of floors comprising a plurality of floor lanterns, one for each car at each floor, call means individual to each floor, a 15 car selecting mechanism individual to each floor including a plurality of stationary contact members, each contact member being individual to a car, a contact arm movable in a single plane, means for preventing movement of the contact member out of said plane and a motive means responsive to operation of the call means at a floor for causing the motive means of the floor selector at that floor to operate the contact arm of that selector to successively engage its contact members 20 until it engages the contact member for the nearest car for the operated call means, and means responsive to the engagement of that contact arm and that contact member for stopping said motive means and for lighting the floor lantern 25 for said nearest car at the floor of the operated call means.

10. A signal system for a bank of elevator cars operable past a plurality of floors comprising a plurality of floor lanterns, one for each car at each floor, call means individual to each floor, a car selecting mechanism individual to each floor including a plurality of stationary contact members, each contact member being individual to a car, a contact arm movable in a single plane, 40 means for preventing movement of the contact member out of said plane, and a motive means having a substantially constant speed characteristic through a variable range of loads responsive to operation of the call means at a floor for causing the motive means of the floor selector at that floor to operate the contact arm of that selector to successively engage its contact members until it engages the contact member for the nearest car for the operated call means, and means responsive to the engagement of that contact arm and that contact member for stopping said motive means for lighting the floor lantern for said nearest car at the floor of the operated call means.

55 WILLIAM F. EAMES.
